UNITED STATES PATENT OFFICE.

CHARLES KLAUBERG, OF NEW YORK, N. Y.

GAS-HEATER.

1,357,329.

Specification of Letters Patent. Patented Nov. 2, 1920.

Application filed January 15, 1920. Serial No. 351,567.

To all whom it may concern:

Be it known that I, CHARLES KLAUBERG, a citizen of the United States, residing at New York, in the county and State of New York, have invented certain new and useful Improvements in Gas-Heaters, of which the following is a full, clear, and exact specification.

This invention relates to gas heaters, and has for its object to provide improved means for generating heat from a gas jet without diminishing the illuminating power thereof. Special objects are to provide a simple and inexpensive heating drum and support therefor, to make said support adjustable so that it may be used with various fixtures and always bring the drum directly over the jet, and to also provide for the vertical adjustment of the drum so that it may be secured at different distances above the jet in order to obtain the best results.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is an elevation of one form of drum and support contemplated by the invention.

Fig. 2 is a plan view of the drum and the adjacent portion of the support.

Referring first to Figs. 1 and 2 of the drawings, 1 designates a gas pipe having the burner or jet portion 2 fitted with the usual tip 3. The support for the heating drum in this instance consists of an upright rod 6 having a bent portion 4 at its lower end provided with a coil 5 to fit over the jet

2, and formed with a series of vertically spaced loops 7 near its upper end. An arm 45 8 has a downwardly bent portion 9 at one end to fit in any one of the loops 7 for supporting the heating drum at different distances above the jet, the other end of said arm having a hook 10 to engage a ring or 50 loop 14 of the supporting bracket 12 of the drum 11. Said drum is bell-shaped with its upper end closed and its lower end open, as shown clearly in Fig. 1, and the bracket 12 has oppositely extending arms with inwardly 55 bent ends 13 to engage correspondingly positioned openings in the walls of the drum. It will be noted that the arm 8 may be made the proper length, according to the length of the bent portion 4 of the upright, so as 60 to bring the drum directly over the jet.

Having thus described my invention, what I claim as new and desire to secure by Letters Patent of the United States is:

1. The combination with a heating drum, 65 of means for supporting the same over a gas jet comprising a standard having a series of vertically spaced loops, and an arm connected to the drum and having a bent portion to engage any one of said loops 70 in the standard for adjustably holding the drum at different distances above the jet.

2. The combination with a heating drum, 75 of means for supporting the same over a gas jet comprising a standard having means of attachment to a gas pipe at its lower end and a series of vertically spaced loops near its upper end, and an arm connected to the drum and having a bent portion to engage any one of said loops in the standard for adjustably holding the drum at different distances above the jet.

In testimony whereof I have signed my name to this specification.

CHARLES KLAUBERG.
